TESTING MACHINE FOR AUTOMOBILE ENGINES

Robert E. Badger, Twin Lakes, Wis., and Raymond G. Knudsen, Kenosha, Wis. (both of 8028 28th Ave., Kenosha, Wis.)

Filed June 10, 1959, Ser. No. 56,293

Term of patent 14 years

(Cl. D52—6)

FIG. 1

FIG. 2

FIG. 1 is a front perspective view of a testing machine for automobile engines, showing our new design, and FIG. 2 is a side elevational view.

The rear of the testing machine not shown is substantially plain.

The characteristic feature of our design for the testing machine disclosed resides in the recessed portion on the right side as shown.

We claim:

The ornamental design for a testing machine for automobile engines, as shown and described.
